UNITED STATES PATENT OFFICE.

WILLIS F. WALKER, OF YORK, PENNSYLVANIA.

RAIL TIE AND FASTENER.

No. 839,972.

Specification of Letters Patent.

Patented Jan. 1, 1907.

Application filed September 26, 1906. Serial No. 336,282.

To all whom it may concern:

Be it known that I, WILLIS F. WALKER, a citizen of the United States, residing at York, in the county of York and State of Pennsylvania, have invented a new and useful Rail Tie and Fastener, of which the following is a specification.

This invention relates to combined rail ties and fasteners; and its object is to provide a metal tie which is of durable construction and which is provided with novel means for fastening rails thereon.

Another object is to provide fastening devices which are adjustable for engagement with the base-flanges of rails or for engaging fish-plates in position upon the rails.

With the above and other objects in view the invention consists of certain novel features of construction and combinations of parts which will be hereinafter more fully described, and pointed out in the claims.

In the accompanying drawings is shown the preferred form of the invention.

In said drawings, Figure 1 is a section on line 1 1, Fig. 2. Fig. 1^a is a side elevation of a portion of the central part of the tie and showing one of the lower tie-straps in end view. Fig. 2 is a plan view of one end portion of the tie. Fig. 3 is a transverse section through the tie with the fasteners removed, said section being taken through the angle-irons and the stop-plates. Fig. 4 is a detail view of one of the combined bottom tie and spacing-straps. Fig. 5 is a top plan view of one of the fasteners. Fig. 6 is a section therethrough. Figs. 7 and 8 are plan and sectional views, respectively, of one of the washers; and Figs. 9 and 10 are similar views of another washer.

Referring to the figures by characters of reference, 1 1 are oppositely-disposed similar channel-irons having their upper flanges 2 and their lower flanges 3 directed inwardly. Arranged upon the upper flanges at desired intervals are metal tie-straps 4, the ends of which are downturned, as at 5, so as to lap the outer faces of the irons 1. Said ends are secured by means of rivets 6 or in any other preferred manner. Similar tie-straps 7 are arranged under the flanges 3, and the upturned ends 8 thereof are secured to the irons 1, as by means of rivets 9. The ends of the channelled irons are connected by bowed end strips 10, which are concavo-convex in cross-

section and are riveted or otherwise secured to the channelled irons 1. A filling 11, of cement or other suitable material, is placed between the channelled irons and the end strips 10, so that the tie is made up of a solid compact mass, which can be firmly seated upon a road-bed.

Arranged upon the channelled irons 1 at proper distances apart and adjacent the end portions thereof are rail-supporting plates 12, having downturned end portions 13, which are adapted to straddle the tie and are formed with outturned flanges 14. Each of these plates is held in place by angle-irons 15, one of which is secured over each downturned portion 13 of plate 12. These angle-irons are proportioned so as to rest upon the flanges 14, while their outwardly-extending portions 16 are substantially flush with the plates 12. The bolts or rivets 17, which are employed for fastening the angle-irons upon the tie, do not extend through the downturned portions 13 of the plates 12, but instead are located close to the opposite edges of said downturned portion and extend through the upturned ends 18 of tie-straps 19, which extend under the irons 1 and the ends 18 of which serve to space the ends of the angle-irons 15 from the irons 1.

Formed within the outturned portion 16 of each angle-iron 15 are alining slots 20, and extending through these slots are bolts 21, the heads 22 of which are disposed beneath the outturned portions 16 and have rounded or substantially semispherical portions 23, from which the bolts proper extend. Each bolt is adapted to extend through fastener members which are similar in construction and each of which consists of a body 24, having a flat base 25, while its opposite face 26 is inclined and provided with a socket 27, from the inner portion of which extends a passage 28, which increases in width toward the base 25. A nose 29 extends from the thickest end of the body 24, and the lower face of this nose is inclined downward, as shown at 30, toward a shoulder 31. All parts of the two fasteners are of the same proportion, with the exception of the shoulder 31. One of the fasteners of each pair has a longer shoulder than the other, and this is for the purpose hereinafter more fully set forth.

The lower fastener 24 has a cup-shaped spring-washer 32 seated in its socket 27, and

this washer is adapted to receive the rounded or ball end 23 of the bolt-head. The socket 27 of the upper fastener 24 receives a washer 33, shaped to fit snugly therein, and a nut 34 of any suitable form is screwed upon the bolt and adapted to force the washer into the socket. A plate 35 is fastened, by means of a rivet 36 or in any other preferred manner, in the lower face of the portion 16 of each angle-iron, and these plates are adapted to limit the movement of the fasteners 24 in one direction. When it is desired to fasten rails to a tie such as herein described, the same are placed upon the plates 12 so as to extend between the slots 20. If a fish-plate 37 is disposed above one of these plates, the fastener 24 having the highest shoulder is placed upon the angle-iron 15, so that its nose 29 will overlap the flange of the fish-plate. The other fastener of the pair is then placed under the portion 16 of the angle-iron, after which a bolt 21, having a washer 32 thereon, is inserted through said fastener and the slot 20 thereabove and through the upper fastener 34, after which the washer 33 is placed in the upper socket 27 and the nut 34 screwed upon the bolt. By tightening the nut the fasteners will be pulled tightly toward each other, and as the bolt rests at an angle to the vertical this tightening operation will tend to draw the upper fastener against the fish-plate and rail-flange, as well as downward thereupon. Where the fastener is only to be used for directly engaging the base-flange of a rail, the one having the smallest shoulder is placed upon the angle-iron.

Importance is attached to the rounded sockets in the fastener and the parts seated therein, because by reason of this construction and arrangement the fasteners are drawn toward each other in both a vertical and horizontal direction. It will be seen that the rail is of a very rigid construction and is free of any parts which are likely to become displaced or broken.

The preferred form of the invention has been set forth in the foregoing description; but I do not limit myself thereto, as I am aware that modifications may be made thereon without departing from the spirit or sacrificing the advantages thereof, and I therefore reserve the right to make such changes as fairly fall within the scope of the claims.

What is claimed is—

55. 1. A rail-tie comprising oppositely-disposed channel-irons having inturned flanges, tie-straps connecting and secured upon the outer faces of the channel-irons, end strips connecting the ends of the channel-irons, said strips being concavo-convex in cross-section, and a plastic filling between the channel-irons and end strips.
2. A tie comprising oppositely-disposed similar channel-irons having inturned flanges,

tie-straps connecting said irons, a rail-plate 65 upon and straddling the channel-irons, angle-irons extending over the end portions of the rail-plate, and fastening means connecting the angle-irons and channel-irons at opposite sides 70 of the rail-plate.

3. A tie comprising oppositely-disposed similar channel-irons having inturned flanges, tie-straps connecting said irons, a rail-plate upon and straddling the channel-irons, said plate having outturned flanges at 75 its ends, angle-irons extending over the end portions of the rail-plate and bearing upon the flanges on said plate, and fastening means extending through the angle-irons and channel-irons at opposite sides of the 80 rail-plate.

4. In a tie the combination with oppositely-disposed channel-irons having inturned flanges, and rigid connections between the irons; of angle-irons secured to the 85 outer faces of the channel-irons and having slots in their outturned portions, and rail-engaging fasteners secured within said slots.

5. In a tie the combination with oppositely-disposed channel-irons having inturned flanges, and rigid connections between the irons; of angle-irons secured to the outer faces of the channel-irons and having slots in their outturned portions, fasteners 90 upon opposite faces of the angle-irons, each 95 fastener having a rail-engaging nose and a socket, bolts extending through the fasteners and slots, said bolts having rounded heads, cup-like washers seated upon the rounded heads and within the adjoining sockets, 100 washers upon the bolts and within the other sockets, and means upon the bolts for clamping the fasteners and the parts therein together.

6. The combination with a tie having an 105 angle-iron secured thereto and provided with an outwardly-extending slotted portion; of a fastener comprising oppositely-disposed members, each consisting of a body 110 and a nose, said members being disposed upon opposite faces of the projecting portion of the angle-irons and having sockets and openings therein, a bolt extending through the openings and through the slot in the angle-iron, a cup-like washer seated within 115 one of the sockets, a washer having a convex face and seated in the other socket, and means upon the bolt for clamping the washers within the sockets.

7. The combination with a tie having an 120 angle-iron secured thereto and provided with an outturned slotted portion; of oppositely-disposed rail-engaging devices upon said slotted portion, and fastening means engaging said devices and the slotted portion and 125 adapted when tightened to impart movement to said devices in horizontal and vertical directions.

8. A rail-tie comprising oppositely-disposed channel-irons, means for rigidly connecting the channel-irons at points between their ends, end strips connecting the ends of the channel-irons, and a plastic filling between and embraced by the channel-irons and end strips.

In testimony that I claim the foregoing as my own I have hereto affixed my signature in the presence of two witnesses.

WILLIS F. WALKER.
